[57] CLAIM

The ornamental design for a hummingbird feeder, as shown.

DESCRIPTION

FIG. 1 is a front top perspective view of a hummingbird feeder illustrating my new design;

FIG. 2 is a top plan view thereof;

FIG. 3 is a front elevational view thereof; and,

FIG. 4 is a bottom plan view thereof.

The broken lines in FIG. 1 are for purposes of illustration only and form no part of the claimed design.

1 Claim, 3 Drawing Sheets

FIG. I.

FIG. 2.FIG. 3.FIG. 4.
